CHISEL SHARPENING JIG

Richard Insalaco, 596 Norwich Parkway,
Quaker Hill, Conn. 06375

Filed Dec. 12, 1972, Ser. No. 314,445

Term of patent 14 years

Int. Cl. D8—05

U.S. Cl. D8—72

FIG. 1

FIG. 2

FIG. 1 is a view in plan of the chisel-sharpening jig of the invention, a chisel mounted therein being fragmentarily shown in phantom lines for illustrative purpose only;

FIG. 2 is a view in end elevation of the jig, the chisel mounted therein being shown in phantom lines for illustrative purposes only;

FIG. 2a is a view in bottom plan of the jig of FIG. 2;

FIG. 3 is an end elevation (similar to FIG. 2) of a modified form of the jig of FIG. 1; and

FIG. 3a is a view in bottom plan of the jig of FIG. 3.

I claim:

The ornamental design for a chisel sharpening jig, as shown and described.
